CENTRIFUGAL DISPLACEMENT APPARATUS

Charles I. Place, New Milford, Conn., assignor to
The Torrington Manufacturing Co., Torrington,
Conn., a corporation of Connecticut

Application September 3, 1943, Serial No. 501,196

10 Claims. (Cl. 230—114)

This invention relates to centrifugal displacement apparatus, and more particularly to centrifugal air blowers, being especially adapted, but not exclusively applicable, to blowers of multiple-discharge type.

It has recently been known to provide a plurality of scroll housings with a single centrifugal blower wheel, so arranged in respect to the housings as to provide for discharge of separate air streams, respectively at lower and higher pressures. An improved and commercially successful construction of this general type is described and claimed in application Serial No. 419,113 filed November 14, 1941, by Edmond Bryan Williams, assignor to The Torrington Manufacturing Co. Since the development of the Williams blower assembly with multiple outlet provisions, there has arisen a need for aircraft blowers with multiple discharge provisions, embodying means for proportioning the total air delivery between the several outlets of the assembly. This result can be accomplished in several ways, as by shifting a partition element dividing a multiple housing, or by shifting a centrifugal blower wheel within a housing which is of somewhat greater depth than the axial dimension of the wheel, but it is desirable, in fact necessary in some cases, to preserve at least a practical running seal between the ends of the wheel and the side members of the housing, irrespective of wheel adjustment therein. Accordingly the present improvements have as a general and major objective, the attainment of the purposes stated.

A further object of the invention is attained in an arrangement, embodying as necessary elements, only a centrifugal blower wheel, a housing thereabout, which may be a scroll housing, and an adjustable inlet ring within the housing which serves particularly advantageously with a wheel of so-called back plate type.

Yet a further object of the invention is attained in an improved form of connection of inlet duct to a centrifugal blower housing with some of the general advantages and possibilities noted in preceding objects.

Still another object of importance is attained in an improved combination of provisions enabling an adaptation of a more or less standardized blower assembly to different installations, wherein the inlet air is derived, at least at times, under appreciable positive, yet variable, pressures; for example, in aircraft installations wherein, in different types of airplanes, because of differences in design of air scoops or air rams, inlet pressures and volumes may vary greatly between

different types of planes, or may vary from time to time in the same installation.

The foregoing and numerous other objects will more clearly appear from the following detailed description of a single preferred embodiment, particularly when considered in connection with the accompanying drawings, in which:

Fig. 1 is a side elevation of a centrifugal blower assembly embodying the present improvements;

Fig. 2 is an end elevational view, taken as viewed toward the low-pressure, higher volume discharge end of the assembly;

Fig. 3 is a horizontal sectional elevation taken along staggered planes as indicated by line 3—3 of Fig. 1, and

Fig. 4 is a vertical section, somewhat enlarged, as taken along line 4—4 of Fig. 1.

Referring now by characters of reference to the drawings, and first to the housing construction, the casing broadly considered, comprises a side plate 10, which may be considered as a front plate, an opposite back plate 11, and a peripheral marginal closure member 12. It will usually but not necessarily be desired to extend the member 12 into an outwardly flared or funnel-like discharge portion 13, which terminates in a hood or auxiliary casing structure generally indicated at 14 which, as will appear, constitutes a form of discharge bell and may serve either for connection into additional discharge duct sections (not shown), or may serve as a housing, complete or incomplete, for a heating unit or the like (not shown). Mounted within the portions 13 and 14 is a fixed, or if desired movable, directioning vane 15 which is disposed in the example shown in a substantially vertical plane, and may be anchored fixedly or adjustably to the curved top element 16 and the bottom element 17 of the structure 13—14.

As will best appear from Figs. 3 and 4, the casing constitutes what is in effect a pair of scroll housing structures in lateral adjacence, but as will appear, with their discharge ducts angularly spaced about the axis of the assembly. One of the scroll housings is also by preference of lesser depth than the other and is identified generally with a chamber structure 20, one side of which is formed by a closure element 21, and the other side of which is formed by the back plate 11 of the housing proper, the shaping of the latter readily appearing from the dotted lines of Fig. 1. A scroll element which in part peripherally bounds the high pressure narrow scroll housing 20, is indicated at 22. As will later appear, the scroll housing 20 surrounds that portion of the centrifu-

gal blower wheel which is most remote from the inlet, and thus, as indicated in the Williams application above designated, serves to receive air delivered at a somewhat higher pressure than that delivered by the portion of the wheel nearer the inlet.

The wider, lower-pressure scroll housing, the chambered part of which is generally indicated at 23, is bounded, as will appear, by the foreplate 10, the closure 21 which serves in part as a partition between the two scroll housings, and the peripheral element 12 above referred to.

Referring now to the wheel structure, the rotor or wheel per se, is or may be of known construction, and is generally indicated at 30. In the form illustrated the wheel is comprised of an imperforate back plate 31, provided with a shaft opening 32 for the reception of the power shaft 33 driven by a suitable motor or the like (not shown). The opposite margin of the wheel 30 is provided with a peripheral ring 34, and this ring and plate 31 are bridged by the usual plurality of parallel, spaced centrifugal blades 35. The blades may, as is preferred, be formed as parts of a one-piece wheel body crimped or otherwise attached to the plate 31 and ring 34, so as to provide a relatively rigid construction capable of withstanding reasonably high speed operation without distortion, warping, or other deformation, even when subjected to the unusual gyroscopic and other stresses incident to usage in high speed aircraft.

Provision for shaft-mounting the wheel 30 includes a hub member 36 provided with a flange 37, secured for example by rivets 40 to the back plate 31. The body of the hub is provided with a tapped aperture for the reception of a setscrew 41, and while the hub may be secured in any suitable manner to the shaft 33, to provide for axial adjustment of the wheel within the housing and along the shaft, a structurally simple provision for this purpose consists in an elongate slot or flat 42. It will now readily appear that by loosening setscrew 41 the wheel 30 may be shifted as desired, to different lateral positions within the housing, hence in different delivery relation to the paired scroll housing structure identified with chambers 20 and 23.

To provide for entrance of the shaft 33 into the casing, the housing back plate 11 is apertured as at 43 to receive the shaft, and it is a preference that the diameter of the opening 43 be such as to provide not appreciably more than a good working clearance with the shaft. If desired, to further enhance the running seal between the back plate end of the rotor and the back plate 11 of the housing, there may be provided an auxiliary plate 44 provided with a center opening which rather snugly receives the shaft 33, the plate 44 being secured as by welding, to the back plate 31 of the wheel.

It will now have appeared that, as is conventional of itself, the wheel 30 is provided with an inlet eye identified with the opening 45 at this end of the wheel. Similarly, the plate 10 of the casing which constitutes a side closure of the scroll housing chamber 23 is also provided with an inlet eye 46, the diameter of which approximates that of the eye 45. It will now have appeared as highly advantageous and in some cases necessary, to assure that even though the axial position of the wheel 30 be varied, for example to increase the delivery to one of the scroll chambers 20 or 23 and proportionately to decrease delivery to the other chamber, provision be made,

irrespective of such adjusted position, to perpetuate the running seal at both ends of the wheel. As to the backplate end of the wheel the plate 31 (imperforate except for the closed shaft opening) and the seal provided between plate 44 and adjacent elements, is such as to assure no appreciable "shunting" of air from the periphery of the wheel back to its interior. At the other or inlet end of the wheel there is provided an adjustable ring bridging the space between the eye 45 and the plate 10 with only a working clearance, so as to perpetuate a running seal in this zone. This ring member internally of the casing, and specifically internally of the scroll housing identified with chamber 23, is indicated at 50. In the example shown this ring constitutes an inward extension of a sleeve, thimble, or conduit section 51, and is of substantially even diameter with the inlet eye 45. In assembly the members 50 and 51 may be taken, in the example shown, as structurally constituting parts of the housing or casing, but at the same time functionally constitute a section or extension of an inlet duct not otherwise shown, the continuing elements of which will usually be connected to this collar structure say through a flared adapter portion 52 and a connecting flange 53.

Provision for quickly and easily effecting desired adjustments of the element 50-51 consists, in the structure shown, of a flange 54 parallel and secured to the foreplate 10 of the casing as by rivets 55. The flange 54 is extended outwardly at a right angle to form an annular, partly cylindrical flange 56 of a diameter just sufficient to receive the member 51. The annular flange 56 is preferably provided with a series of spaced slots 57, enabling as will appear, the flange 56 to be constricted upon or contracted about the collar 51, provision for this clamping action being made by a clamp ring 58, having a pair of upstanding tabs or ears 60 apertured to receive a screw or bolt 61, this clamp per se being of conventional form apart from combinations.

It will now be obvious that, upon loosening the bolt 61, or nut thereon, the contractile band 58 being resilient in nature, will open sufficiently to permit sliding movement of the collar 51, hence of ring 50 in a direction axially of the wheel, so that the collar may be projected various distances into the casing and low pressure scroll housing. It is suggested as usually advantageous first to adjust the member 50-51 just to contact the ring 34 of the wheel 30 after the latter is adjusted desirably, then to back off the collar 50-51 to an extent just to provide the requisite working clearance.

The function and operation of the assembly are now thought to have become fully apparent from the description of parts, but it may be noted for completeness that air entering the inlet conduit, thence the end section thereof identified with elements 52, 51 and 50, will enter the wheel 30, whence it is impelled by centrifugal action in well known manner, outwardly into the two scroll chambers 20 and 23. The higher pressure component of air delivered from the wheel will emanate from that zone nearest the back plate 31 and hence will be impelled outwardly of the wheel into the discharge portion of the high pressure scroll housing, the outlet or discharge conduit connection of which is generally indicated at 62. It will have appeared from the description of housing structure that the member 22, serving as a scroll element, terminates somewhat abruptly and in a region close to the periphery of the

wheel in a reversely curved cutoff portion 63. The same general structure and function appear in the lower pressure side of the casing, specifically in the lower pressure scroll housing chamber 23, the scroll structure of the latter being identified with the member 12 which, as will appear, terminates near the discharge, in a cutoff zone 64 relatively close to the periphery of the wheel, beyond which the discharge connection from the casing, for low pressure air, is found in the elements 13 and 14 heretofore described.

As before noted, in case a specific installation may require, for example, a lesser volume of air through the high pressure discharge 62, and a greater volume of air through the lower pressure discharge 13-14, the wheel 30 will be adjusted to bring it further to the left (Fig. 4) by backing off set screw 41 and axially shifting the wheel, thereafter tightening the screw 41. Meanwhile the collar 50-51 will have been freed from clamped securing by loosening the bolt 61, retracting the collar sufficiently for wheel adjustment, thereafter setting the collar to the wheel in its adjusted position, then backing off the collar 50-51 preferably only enough to provide a working clearance and to maintain the described running seal in the inlet region of the wheel and housing.

It should be noted that the adjustable inlet provision, although of particular advantage in the multiple discharge assembly as described, is nevertheless useful as an improvement in single discharge blower assemblies wherein, say for purposes of axial expansion or otherwise, the housing is of somewhat greater width than the length of the wheel, and in other cases wherein it is desired to provide for adjustment of elements laterally of the wheel, the adjustable inlet provision is found advantageous. It should also be noted that while the single example selected for description discloses the combination including one or more scroll chambers about the wheel, the adjustable inlet provision is not necessarily restricted to use in this combination.

Although the invention has been described by making particular reference to a single selected embodiment of present improvements, the detail of description is to be understood in an instructive, and not in any limiting sense, many variants being possible within the scope of the claims appended.

I claim as my invention:

1. In a rotary fluid displacement device, a rotor, a housing about the rotor having an inlet opening adjacent the inlet area of the rotor, means dividing the housing to provide a multiple discharge therefrom, means for varying the operative relation of the rotor to the parts of the housing whereby to vary the proportion of fluid delivered to the various avenues of discharge, and adjustable means for maintaining a constant relation between housing inlet and rotor inlet, irrespective of variation of said proportioning means.

2. In a centrifugal fluid displacement device, a centrifugal rotor, a housing about the rotor having an inlet opening adjacent the inlet area of the rotor, means dividing portions of the housing to provide a multiple discharge therefrom, means for varying the operative relation of the centrifugal wheel to the separate portions of the housing, whereby to proportion the fluid delivered to the various avenues of discharge, and an adjustable inlet element disposable in vari-

ous positions internally of the housing for maintaining a constant relation between housing inlet and rotor inlet, irrespective of variation of said proportioning means.

5 3. In a centrifugal blower assembly of multiple discharge type, a centrifugal rotor, a housing of somewhat greater axial depth than the rotor, and including separate discharge outlets having openings in different zones axially along the rotor, means enabling the rotor to be adjusted to various positions along its axis and depthwise of the housing, the housing and the rotor being formed for maintaining a running seal at each end of the rotor, irrespective of adjusted position of the rotor within the housing.

10 4. In a multiple discharge centrifugal blower assembly, a centrifugal blower wheel, a housing about the wheel provided with axially spaced discharge conduits, the housing being of greater axial depth than the length of said wheel, and adjustable to various axial positions depthwise of the housing, the blower wheel being provided with sealing means at one of its ends, and sealing means at the opposite end of the wheel adjustable to maintain an operating seal between the last said end of the blower wheel, and the adjacent side of the housing, irrespective of the wheel adjustment therein.

15 5. In a centrifugal blower assembly of double discharge type, a double scroll housing, a single centrifugal wheel serving the double housing, means providing a running seal between the wheel and housing in each end region of the wheel, means for adjusting the axial relation of the wheel to the two scroll housings, whereby to effect a variably proportionate delivery to the respective scroll housings, and one of said seal-forming means including an element adjustable to and from the wheel to preserve the running seal at the adjacent end of the wheel irrespective of the axial relation of the wheel to the scroll housings.

20 6. In a centrifugal blower assembly of double discharge type, a double scroll housing, a single centrifugal wheel serving the double housing, means providing a running seal between the wheel and housing in each end region of the wheel, means for adjusting the axial relation of the wheel to the two scroll housings whereby to effect a variably proportionate delivery to the respective scroll housings, and one of said seal means including a tubular section forming part of an inlet conduit associated with the housing, said tubular section being adjustable toward and from the wheel.

25 7. In a centrifugal blower wheel assembly, a centrifugal blower wheel, a housing within which the wheel is operable and provided with an inlet eye, an annular flange external of the eye, an inlet conduit extending into the flange and into the eye and adjustable depthwise of the housing, and a contractile band disposed externally of the flange, and adapted to clamp the flange to the conduit.

30 8. In a multiple discharge blower assembly, a casing structure having a side inlet, a centrifugal blower wheel having a single end inlet, and operatively arranged in the casing structure, the casing structure including a relatively shallow high pressure scroll housing, and a relatively deeper lower pressure scroll housing located nearer the inlet zone of the casing, a partition at least partly separating the housings, a sealing member adjustably bridging the inlet end of the

wheel and the corresponding end of the casing, both the wheel and said sealing member being adjustable in a direction axially of the wheel, and a sealing plate between the opposite end of the wheel and the adjacent end of the casing structure.

9. In a centrifugal blower assembly of double discharge type, a double scroll housing, a single centrifugal wheel serving the double housing, the axial length of the wheel being somewhat less than the corresponding internal dimension of the housing, whereby to enable axial adjustment of the position of the wheel across the housing, means for adjusting the axial relation of the wheel relative to the two scroll housings, whereby to effect a variably proportionate delivery of air to the respective scroll housings, an element adjustable to and from the wheel to maintain a running seal at one end of the wheel, said element arranged to deliver air directly to the interior of the wheel irrespective of the varying axial wheel adjustment, and a sealing plate at

the other end of the wheel, said plate and element providing a seal between the wheel and the housing at the opposite wheel ends.

10. In a centrifugal blower assembly of double discharge type, a double scroll housing, a single centrifugal wheel serving the double housing, the wheel being characterized by a substantially full diameter inlet opening at one end, and a substantially imperforate back plate at its opposite end, means for adjusting the axial relation of the wheel to the two scroll housings, whereby to effect a variably proportionate delivery of air to the respective scroll housings, and means providing a running seal between the wheel and housing in each end region of the wheel, said means including near the inlet end of the wheel, a tubular section forming part of an inlet conduit associated with the housing which section is adjustable toward and from the wheel, and a sealing plate at the opposite end of the wheel.

CHARLES I. PLACE.
